UNITED STATES PATENT OFFICE.

CHARLES H. MASTEN, OF FREMONT, NEBRASKA.

BICYCLE-LOCK.

SPECIFICATION forming part of Letters Patent No. 640,297, dated January 2, 1900.

Application filed October 5, 1899. Serial No. 732,664. (No model.)

To all whom it may concern:

Be it known that I, CHARLES H. MASTEN, a citizen of the United States, residing at Fremont, in the county of Dodge and State of Nebraska, have invented a certain new and useful Bicycle-Lock, of which the following is a specification.

My invention relates to padlocks of the permutation type; and the object thereof is to provide a cheap, simple, and durable device of the kind described which can only be opened or unlocked by a person conversant with a pre-arranged combination.

My invention consists in certain parts and combination of parts, which will be specifically described in the following specification, recited in the claims, and illustrated in the drawings forming a part hereof, and in which—

20 Figure 1 is a front elevation of a lock constructed in accordance with my invention. Fig. 2 is a vertical longitudinal section through the same, showing the parts in the position they assume when the lock is open. 25 Fig. 3 is a similar view showing the position of the parts when the device is closed. Fig. 4 is a vertical sectional view taken on the line 4-4 of Fig. 2, and Fig. 5 is a fragmentary detail view of the several cam-disks.

30 Referring now to the drawings by reference-numerals, 10 indicates the lock-case, having a substantially rectangular recess 11, in which is slidably secured rectangularly the shackle-carrying frame 12, from which the shackle 13 depends and projects through a slot 14 in the end of the case. The lock-case is provided with an upwardly-projecting pin 14^a, on which is loosely mounted the disk-tumbler 15, cut away to provide a straight 40 side 16, whereby the disk is adapted to exert a cam action upon the upper bar 17 of the shackle-frame 12. This disk is provided with a segmental slot 18, (about a quadrant,) as will be more fully described hereinafter. 45 19 is a similar disk-tumbler journaled concentric with the first-named tumbler and provided with a substantially semicircular slot 20, registering with the slot 18.

21 is a tumbler-throwing disk carrying a pin 50 22, working the slots 18 and 20 of the tumbler,

sleeved on the pin 14^a, and carrying a central circular shoulder 23, projecting through a registering opening in the lock-case cover 24 and rigidly secured to the indicating-star 25 by means of pins 26, said star indicating 55 the several points of the combination on the graduated scale 27 of the lock-case cover.

28 are two upwardly-projecting lugs connected to the bar 29 by means of links 30, and extending from said bar 29 is a chain 31, on 60 the end of which is a swivel-line 32 for engagement with the shackle-hook when it is desired to use the device as a bicycle-lock.

The operation of my device is as follows: All the parts being assembled and lying in 65 the position shown in Fig. 2, the shackle will be unlocked. Now suppose it is desired to apply the lock. The indicating-wheel is turned to the left or right several times, carrying the tumbler-throwing disk within and by 70 means of the pin 14^a rotating the tumblers until they form a complete circle, as shown in Fig. 3, thereby raising the shackle-frame and locking the hooked end of the shackle within the lock-case.

Having thus fully described my invention, what I claim as new, and desire to secure by Letters Patent of the United States, is—

1. The combination with a case having a rectangular recess therein, of a pin projecting 80 from said case centrally of the recess, a shackle-carrying frame slidably in said recess and surrounding said pin, a plurality of cam-tumblers loosely journaled on said pin and adapted to slide the shackle-carrying frame 85 and means for actuating the tumblers, substantially as described.

2. The combination with a casing having a rectangular recess, a shackle slidably secured in said recess and projecting through the casing, the cam-tumblers 15 and 19 journaled concentric of the recess and adapted to slide the shackle and lock the same and an indicator-wheel carrying a disk on which is a pin to rotate the tumblers, substantially as de- 95 scribed.

CHARLES H. MASTEN.
